UNITED STATES PATENT OFFICE.

DAVID C. KLAUSMEYER AND HENRY M. NORRIS, OF CINCINNATI, OHIO, ASSIGNEES
TO THE CINCINNATI BICKFORD TOOL COMPANY, OF CINCINNATI, OHIO, A COR-
PORATION OF OHIO.

CONSTANT-DRIVE RADIAL DRILL.

Application filed March 23, 1925. Serial No. 17,605.

This invention relates to radial drilling and tapping machines and it deals more particularly with the means for actuating the various mechanisms thereof such, for example, as the arm elevating and lowering mechanism, the drill-head translating mechanism, the spindle rotating mechanism and the spindle feeding mechanism.

Machine tools of this character are usually constructed with a base, an upright column, and a laterally projecting arm upon which the drill-head is adjustably mounted. Power to rotate the drill spindle and to feed it vertically in the drill-head is usually provided by a motor or other prime-mover located either on a rearward extension of the arm or on the base at the foot of the column, and the power therefrom is transmitted through suitable mechanism to a shaft journal lengthwise of the radial arm, and thence through suitable change-gear mechanism to the drill spindle.

As is well understood by those skilled in the art, it is essential that means be provided for regulating the speed of rotation of the drill spindle inasmuch as the varying diameters of the drills and taps and the nature of the work being operated on, each present working conditions which require different speeds of rotation of the spindle to produce maximum efficiency in operation.

To provide these various speeds, it has heretofore been customary to locate, adjacent the prime-mover, a change-gear mechanism capable of transmitting about six different speeds from a single speed received from the prime mover. The differences in ratio afforded by this so-called "speed-box" control are necessarily small since there is considerable mechanism actuated thereby and great differences in ratio would effect abrupt changes and cause strains that would be detrimental to the parts.

Coarser changes are provided by a change-gear mechanism located in the drill-head. These latter change gears are known as the "back-gears" and usually provide four speed changes which multiply the speeds provided by the speed-box into about twenty-four speeds in the spindle. Inasmuch as only the

spindle rotating and translating mechanism is actuated by the back-gears, the speed changes provided therein may be materially greater than those provided in the speed-box.

Another well known way of providing the necessary number of speed changes is to replace the single speed prime mover and the speed-box with a variable speed motor capable of being operated at a plurality of speeds corresponding to the speeds produced in other machines by the speed-box, and combining therewith the usual back-gears in the drill-head.

To effect a predetermined speed in the spindle, it has heretofore been necessary for the operator first, by the manipulation of certain control levers carried by the drill-head, to shift the back-gears and thereby obtain the nearest approximate speed obtainable therein; and then, to leave his position at his work and go to the opposite end of the machine where, by manipulation of the speed-box control lever, or the motor controller whichever the case may be, effect the finer and more accurate speed setting. This remote and inconvenient location of the finer speed regulating mechanism makes its frequent manipulation unhandy and bothersome and therefore the tendency of the operator is to ignore the finer speed settings and to utilize the nearest speed obtainable in the back-gears, which he may shift from a position at his work. This employment of the improper spindle speed necessarily reduces the efficiency of the machine-tool.

Another disadvantage of these prior constructions is that inasmuch as great power must frequently be transmitted at slow speed the parts of the transmission must necessarily be made of a size and strength sufficient to withstand the strain imposed during such slow transmission and therefore the parts are unduly heavy and objectionable at the time when the mechanism must be driven at a materially faster rate.

This invention has for an object to provide a radial drill with a constant speed prime mover and a constant speed power transmission extending into the drill-head,

adjustably mounted on the arm, and to locate all of the speed change mechanism within the adjustably mounted drill-head; thereby providing a constant speed driving connection from the prime mover to the drill-head, and locating within easy reach of the operator when stationed at his work all of the speed controlling levers.

A further object is to overcome certain structural difficulties in prior radial drills by providing a constant rate high speed drive from a constant speed prime mover to the drill-head and to utilize the constant speed drive to actuate various other mechanisms embodied in the radial drill.

Still another object of this invention is to provide means selectively to rotate the spindle of a radial drill at any one of a plurality of different speeds and to provide means to translate the spindle in the drill head, and so to arrange the spindle rotating mechanism and the spindle translating mechanism that the latter will not be affected by variations in the former.

Still another object of this invention is to combine entirely within the drill-head, a plurality of sets of speed change devices operative in conjunction with the usual back-gears to produce thirty-two speeds in the spindle from a single speed in the prime mover.

A further object of this invention is to provide in a radial-drill a spindle and means selectively to rotate it at any one of the usual number of speeds and to provide means unaffected by the changes in speed in the spindle for translating the arm on the column and for translating the drill-head on the arm.

Another object of this invention is to provide, in a radial drill having an arm shaft and means to rotate the spindle from the arm shaft, means to disconnect the spindle from its arm shaft and simultaneously therewith to apply a brake to the spindle rotating means.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is a side elevation, partly in section of a radial drill embodying the present invention. Fig. 2 is a development of the mechanism contained in the drill-head showing the means for securing thirty-two speeds in the spindle from a single-speed in the arm shaft and for actuating the spindle translating mechanism independently of the spindle

speed changes. Fig. 3 is a detail plan showing the means for actuating the drill-head power traverse from the constant speed arm shaft, the controlling lever for the power traverse being shown as swung upwardly about 90° from its normal position for the sake of clearness. Fig. 4 is a side elevation, partly in section, of the mechanism shown in Fig. 3. Fig. 5 is a section on the line 5—5 of Fig. 3. Fig. 6 is a side elevation of Fig. 5. Fig. 7 is a left end elevation of the radial arm showing more particularly the means for adjustably mounting a coolant pump and actuating it from the constant speed arm shaft. Fig. 8 is a diagrammatic view showing the gearing at the upper end of the column for transmitting power from the upright power shaft in the column to the arm translating screw and to the horizontal arm shaft. Fig. 9 is a detail view showing a lubricant pump actuated by the constant speed power transmission.

Referring more particularly to the drawings, the invention is disclosed as embodied in a radial drilling and tapping machine comprising a base 1, an upright column 2, a horizontal arm 3, and the usual tool-head 4 slidably mounted on guides 5 carried by the arm. The column preferably comprises a central post 6, and a sleeve 7 rotatably journaled on the post. The arm 3 is formed with a girdle 8 slidably mounted upon the cylindrical portion 7a of the sleeve 7 and is adapted to be raised and lowered thereon by means of a screw 9 journaled in bearings 10 and 11 provided by the sleeve and having a threaded engagement with the arm 3 as is usual in this type of machine tool. Rotatably and translatable journaled in the head 4 is a tool-spindle 12 adapted to receive the tools commonly used in radial drilling and tapping machines.

Power to rotate and translate the tool spindle, to move the drill-head lengthwise of the arm 3, and to elevate and lower the arm on the sleeve 7 is preferably furnished by a single speed prime mover 13 located in any suitable place, such for example as on the base 1 adjacent the foot of the column 2. This prime mover may consist of a pulley, as shown in the drawings, or if desired, it may consist of a constant speed motor. In the embodiment illustrated, power from the prime mover flows through a horizontal shaft 14 journaled in the base of the column and is transmitted, by bevel gears 15 and 16, to an upright shaft 17 journaled coaxial with the column. The shaft 17 carries, at its upper end, a gear 18 (see Figs. 1 and 8) which, through an idler gear 19, drives a gear 20 fixed upon a shaft 21 journaled in bearings 22 and 23 provided by the sleeve 7. A gear 25 is fixed to and rotates with the gear 19. The arm translating screw 9 is adapted to be rotated, in reverse directions from the upright shaft 17. To this end, the screw 9 car-

ries at its upper end a gear 24, and a tumbler gear 25^a serves to connect the gears 18 and 24 directly as shown in full lines in Fig. 8 to rotate the screw in a direction to lower the arm or indirectly through gears 19 and 25 as shown in dotted lines in Fig. 8 to rotate the screw in the opposite direction to elevate the arm.

Journalized lengthwise of the arm 3 is a shaft 26 having secured to it at its rear end a bevel gear 27 permanently in mesh with a bevel gear 28 journalized in the girdle and having a splined connection with the shaft 21. From the foregoing, it will be perceived that the arm shaft 26 will be rotated continuously from the prime mover at a constant speed in all of the vertical positions of the arm on the column.

Power is taken from the arm shaft and delivered to a shaft 29, rotatably journalized in the drill-head, by a frictional reversing clutch mechanism C which is similar in construction to that forming the subject of Re-issue Patent No. 14,755 dated Nov. 18, 1919, to H. M. Norris. This reversing mechanism comprises bevel gears 30 and 31 loosely journalized on a sleeve 32 splined to the shaft 26 and permanently meshing with the opposite sides of a bevel gear 33 carried by the shaft 29. Either of the gears 30 or 31 selectively may be secured to the sleeve by frictional clutches controlled by a shiftable collar 34 as fully explained in said patent. The collar 34 may be shifted to either of its operative positions by a lever 35 located within easy reach of the operator when stationed at his work. It will readily be perceived that inasmuch as the gears 30 and 31 act upon the gear 33 at diametrically opposite sides they will transmit to said gear oppositely directed rotary motion.

The motion received by the gear 33 and shaft 29 is transmitted to the spindle 12 through suitable speed change mechanisms which provide means for varying the speed of rotation of the spindle. Thus, by the manipulation of suitable levers carried by the drill-head the gears of the speed change mechanisms may be so meshed as to produce the speed best suited to the tool being used and to the work being operated on. As shown in Fig. 2, these speed changes may be effected by three separate change gear sets X, Y and Z. The gear set X comprises gear units 36 and 37 splined upon the shaft 29 and providing gears 36^a, 36^b and 37^a and 37^b respectively. These gears are adapted selectively to be meshed with gears 38^a, 38^b and 39^a, 39^b provided by gear units 38 and 39 fixed to a shaft 40 also journalized within the drill-head. Thus by selectively meshing these gears four speeds may be transmitted to the shaft 40 from a single speed in the shaft 29.

The gear unit 39 also provides a gear 39^c which is adapted to be meshed with a gear

41^a provided by a gear unit 41 splined to a shaft 42 journalized in the drill-head parallel to the shaft 40. A gear 41^b which is adapted to be meshed with the gear 39^a is also provided by the gear unit 41. The gears 39^a, 39^b, 70 41^a and 41^b constitute the gear set Y which serves to double the four speeds produced by the gear set X.

The tool spindle 12 is translatable but non-rotatably journalized in a sleeve 43 journalized in the drill-head 4. Rotation is transmitted from the shaft 42 to the sleeve 43 and thereby to the spindle by means of the gear set Z usually known as the "back-gears" which provide four speeds thereby multiplying the eight 80 speeds in the shaft 42 into thirty-two speeds in the spindle. This gear set comprises a gear unit 44 splined to the shaft 42 and providing a gear 44^a and a clutch-member 44^b. Rotatably journalized on the sleeve 43 is a gear unit 45 providing a gear 45^a with which the gear 44^a is adapted to be meshed, and a gear 45^b permanently in mesh with a gear 46^a provided by a gear-unit 46 secured upon a shaft 47 journalized in line with the shaft 42. The gear-unit 46 also provides a clutch member 46^b adapted to be engaged by the clutch member 44^b. A small gear 48, later to be referred to, also is secured to the shaft 47. Splined to the sleeve 43 is a gear-unit 49 providing a gear 49^a, adapted to mesh with the gear 48, and clutch member 49^b adapted to engage the gear 45^b. From the foregoing, it will be seen that the gear unit 45 may be rotated either by the gear 44^a or by the gear 46^a through the clutch 44^b-46^b. By shifting the clutch member 49^b into engagement with the gear 45^b these two speeds are transmitted to the sleeve 43 and thereby to the spindle. The gear unit 46, and thereby the shaft 47 and gear 48, also receives two speeds from each speed in the shaft 42. One of these speeds is obtained through the engagement of the clutch members 44^b and 46^b and the other is obtained through gears 44^a, 45^a, 45^b and 46^a. Thus by selectively meshing the gears and clutches any one of thirty-two speeds may be produced in the spindle from a single speed in the arm shaft.

Intermediate its ends the spindle 12 is rotatably journalized in a sleeve 50 translatable but non-rotatably journalized in the drill-head 4. Thrust-bearings 51 and 52 carried by the spindle at the opposite ends of the sleeve 50 prevent relative axial movement between the spindle and the sleeve. A toothed rack 53 carried by the sleeve 50 is engaged by a pinion 54 rotatably journalized in the drill-head and therefore rotation of the pinion, by means later to be described, causes vertical movement of the sleeve 50 and the tool spindle to cause the tool carried by the latter to penetrate and emerge from the work.

Power to rotate the pinion 54 thereby to translate the tool spindle is preferably taken

from the constant speed shaft 29, independent of the change gears thereon. This is effected through a gear 55 fixed to the shaft 29 which meshes with and drives a gear 56 carried by a shaft 57 also journaled vertically in the drill-head. Fixed upon the shaft 57 is a cone of gears comprising gears 58, 59, 60, 61, 62 and 63 maintained permanently in mesh with gears 64, 65, 66, 67, 68 and 69, respectively, 10 loosely journaled on a hollow shaft 70 rotatably carried by the drill-head. The shaft 70 is formed in one side with a slot 71 through which is adapted to project the head 72^a of a spring pressed drive key 72 pivoted within a slot 73 in a rod 74 axially movable in the hollow shaft 70. The rod 74 is formed with an annular rack-teeth 74^a which mesh with a pinion 75 adapted to be rotated by a lever 76 carried by the drill-head 4. By shifting the 20 rod 74 lengthwise the head 72^a of the key 72 may be caused selectively to engage any one of a plurality of notches *n* formed in the gears 64, 65, 66, 67, 68 and 69 thereby to effect a driving connection between the shafts 25 57 and 70 at any one of six available speeds. To the shaft 70 is secured a worm 77 which meshes with a worm-wheel 78 secured to the pinion 54. Thus it will be seen that means is provided for translating the drill-spindle 30 from the constant speed shaft 29 and that the rate of translation may be varied without affecting the speed of rotation of the drill spindle and vice versa. The shaft 70 may also be rotated by a hand-wheel 79 having a notch 35 79^a which engages a drive-key 80, also carried by the rod 74, and projecting through a slot 81 in the shaft 70. The keys 72 and 80 are so arranged that the manual feed is effective only when the key 72 is in its intermediate position, as shown in Fig. 2, in which 40 the power feed is ineffective.

The constant speed arm shaft is also utilized to actuate a power traverse for the drill-head. This traverse comprises a shaft 82 45 journaled in the drill-head and carrying a worm 83 adapted to drive a worm wheel 84 carried by one end of a shaft 85 also journaled in the drill-head. The opposite end of the shaft 85 carries a pinion 86 meshing with a rack-bar 87 secured lengthwise of the radial arm. Thus rotation of the shaft 82 in one direction effects translation of the drill-head toward the column and rotation of the shaft in the opposite direction translates the head 55 away from the column. Power to rotate the shaft 82 is taken from the arm shaft by a gear 89 rotatably journaled in the drill-head and having a splined connection with said arm shaft. The gear 89 drives a similar gear 90 60 carried by a shaft 91 journaled in the drill head and carrying at one end a pulley 92. Also journaled in the drill-head, in bearings 93 and 94 is a shaft 95 carrying at its upper end a pulley 96 adapted to be driven, by a belt 65 97, from the pulley 92. The shaft 95 carries,

at its lower end a bevel gear 98 permanently in mesh with bevel gears 99 and 100 loosely journaled on the shaft 82 and adapted selectively to be clutched by a shiftable clutch element 101 carried by a rod 103 slidably mounted in the shaft 82. For the purpose of shifting the clutch member 101, there is attached to the rod 103, by means of a pin 104 passing through slots 105 in the shaft 82, a cylindrical rack 106 which is engaged by a pinion 107 carried by a shaft 108 rotatably and translatably journaled in the drill-head 4. Manual means also is provided to rotate the shaft 82 to effect translation of the drill-head. This comprises a hand wheel journaled coaxial with the shaft 82 and carrying a clutch-element 109 which is adapted to be engaged by a similar clutch element 110 splined to the shaft 82. A spring controlled bell-crank lever 111, pivoted at 112, normally holds the 70 clutch-elements 109 and 110 together to connect the manual drive for the shaft 82. As shown in Fig. 3, the lever 111 has a portion bearing against the pinion and therefore inward movement of the pinion, prior to its 75 rotation to shift the clutch member 101, swings the bell-crank about its pivot and disconnects the clutch elements 109 and 110. A lever 113 pivoted to the shaft 108 serves to 80 translate and rotate that shaft. 90

To overcome the momentum of the drill-head and its translating mechanism when power drive is rendered ineffective, the shaft 82 carries a brake-drum 114 adapted to be engaged by a brake-shoe 115 carried by a spring-pressed lever 116 pivoted at 117 in the drill-head. During the power traverse of the drill-head the brake-shoe is held out of engagement with the brake-drum by a cam 118 which is forced into contact with the lever 116 by a cam 119 on the shaft 108. When the lever 113 is moved to shift the clutch member 101 to its neutral position the low portion of the cam 119 is brought adjacent the bar 118^a attached to the cam 118, thereby permitting 105 the cam 118 to be moved back from the lever 116 whereupon the spring *s* attached to the lever 116 forces the brake shoe into contact with the brake drum. 110

The constant speed power transmission 115 from the prime mover to the drill-head may also be utilized to great advantage to operate a coolant pump to supply a constant stream of coolant to the tool. This pump may be located at any suitable place and connected with any part of the constant speed transmission but it is preferably carried by the girdle 8 of the arm and driven from the arm shaft 26. As shown in Fig. 7, a pump *P* is carried by a base 120 pivotally supported at 121 upon a bracket 122, affixed to the girdle 8. A continuous belt 123 passes about the pump pulley and is driven from a pulley 124 on the arm shaft 26. It will readily be perceived that 120 due to the location of the pivot 121 the pump 125 130

base may be swung downwardly to tighten the belt 123 and it may be clamped in its adjusted position by a clamp lever 125. The pump P is adapted to draw coolant from a 5 reservoir R in the base 1 through a flexible tube 126 which permits movement of the arm about the column and also vertical movement of the arm on the column. The coolant drawn up by the pump is forced through a 10 flexible tube 127 and delivered by a nozzle 128 to the tool.

Still another advantage gained by the use of a constant speed transmission to the drill-head is that this transmission may be used 15 more effectively and more satisfactorily to actuate a continuous lubricating system for the gears and bearings in the drill-head. Fig. 9 shows a reservoir " formed in the drill-head and lubricant pump L actuated from the 20 constant speed shaft 29, journaled in the drill-head, through bevel gears 129 and 130. Inasmuch as the rest of the lubricating system for the gears and bearings in the drill head is substantially the same as that shown 25 in United States patent to D. C. Klausmeyer No. 1,653,576 dated Dec. 2, 1927, further illustration and description thereof is deemed unnecessary in this application.

From the foregoing, it will be seen that 30 many advantages have been gained by providing a constant speed transmission from the prime mover to the drill-head. Not only does this constant speed transmission permit the convenient manipulation of all of the 35 speed change devices from the operator's position at his work but it also permits all of the trains of mechanism to be actuated independently of the speed of rotation of the spindle.

Without further analysis, the foregoing 40 will so fully reveal the gist of this invention that others can, by applying current knowledge, readily adapt it for various utilizations by retaining one or more of the features that, 45 from the standpoint of the prior art, fairly constitute essential characteristics of either the generic or specific aspects of this invention and, therefore, such adaptations should be, and are intended to be, comprehended 50 within the meaning and range of equivalency of the following claims.

Having thus revealed this invention, we 55 claim as new and desire to secure the following combinations and elements, or equivalents thereof, by Letters Patent of the United States:

1. A radial drill combining a column; an arm supported by the column; a drill-head carried by said arm; a spindle rotatably journaled in the drill-head; a constant speed power transmission extending along said arm; and three serially arranged and independently controlled gear sets embodied in said head for variably driving said spindle 60 from said single speed power transmission.

2. A radial drill combining a column; an arm supported by the column; a drill-head adjustably mounted on the arm; a spindle rotatably journaled in the drill-head; a tool carried by the spindle; a shaft extending 70 lengthwise of the arm; a single speed prime-mover connected to rotate said arm shaft at a constant rate; speed change mechanism embodied in said head for rotating said spindle at a plurality of rates from said arm shaft; 75 means actuated by said arm shaft to translate the drill-head on the arm; a reservoir; and a coolant system including a pump actuated by said constant speed arm shaft to draw coolant from said reservoir and apply it to said tool. 80

3. A radial drill combining a column; an arm extending horizontally from said column; a drill-head adjustably mounted on the arm; a spindle rotatably journaled in said drill-head; a single speed prime-mover adjacent the base of the column; a shaft operatively connected with the prime-mover and extending upwardly through the column; a screw journaled exteriorly of said column and having a thrcaded connection with said arm; a second shaft journaled exteriorly of said column; single speed driving means connecting said first named shaft with said screw and with said second shaft; a shaft journaled lengthwise of said arm; a single speed driving connection between said second shaft and said arm shaft; means actuated by said single speed arm shaft to translate said drill-head on said arm; and a plurality of independently operative speed change devices also located 90 in said drill-head and connecting said arm shaft with said spindle to rotate the tool at 100 various speeds.

4. A radial drill combining a column; an arm supported by the column; a drill-head carried by the arm; a spindle rotatably and translatable journaled in the drill-head; a constant speed power transmission extending along said arm; means carried by said drill-head for selectively rotating said spindle at 105 any one of more than six speeds from the single speed in the constant speed transmission; and means operated directly from the constant speed transmission for translating the spindle.

5. A radial drill combining a column; an arm supported by the column; a drill-head carried by the arm; a spindle rotatably and translatable journaled in the drill-head; a constant speed power transmission extending 110 along said arm; a shaft journaled in the drill-head; a single speed driving connection between said constant speed transmission and said shaft; means intermediate said shaft and said spindle for selectively rotating the latter from the former at any one of a plurality of speeds; and a spindle translating mechanism actuated directly from said shaft.

6. A radial drill combining a column; an arm supported by the column; a drill-head 115

carried by the arm; a spindle rotatably and translatable journaled in the drill-head; a prime mover; a constant speed power transmission operatively connected with said prime mover and extending along said arm; means carried by the drill-head and actuated by said constant speed transmission for rotating said spindle at any one of a plurality of speeds; means carried by the drill-head and actuated directly from said constant speed transmission for translating said spindle; and means for varying the speed of rotation and speed of translation of the drill spindle each without affecting the other.

15 7. In a radial drill, a drill-head; a constant speed power shaft transmitting power to said drill-head; a constant speed shaft journaled in said drill-head and adapted to be rotated from said power shaft; a spindle rotatably and translatable journaled in the drill-head; spindle rotating means comprising a plurality of sets of speed change gears for selectively rotating said spindle at any one of a considerable number of speeds from the single speed in said constant speed shaft; a spindle translating mechanism actuated by said constant speed shaft independently of said spindle rotating means; and means to vary the speed of translation of said spindle.

20 8. In a radial drill, an arm; a drill-head mounted on the arm; a constant speed power shaft carried by the arm and transmitting power to said drill-head; a second shaft, journaled in the drill-head and rotated by said power shaft at an invariable speed; a spindle rotatably and translatable journaled in the drill-head; a plurality of sets of speed change gears intermediate the said second shaft and the spindle; a third shaft geared to said second shaft; means actuated by said third shaft to translate said spindle, said means including a fourth shaft; a cone of gears on said third shaft; a cone of gears loosely journaled on said fourth shaft, said cones of gears being 25 permanently in mesh; and means to render any pair of said gears to transmit power to said fourth shaft.

9. A radial drill combining a column; an arm supported by the column; a drill-head carried by the arm; a constant speed shaft journaled lengthwise of said arm; a second constant speed shaft, journaled in said drill-head and driven by said arm shaft; a drill spindle rotatably journaled in said drill-head; a plurality of sets of speed change gears operatively connecting said second shaft with said spindle for rotating said spindle at any one of a plurality of speeds; a reservoir in the drill-head and a lubricant pump driven by 30 said second constant speed shaft and adapted to take lubricant from said reservoir and apply it to said gears.

10. A radial drill combining an upright column; a horizontally disposed arm supported by said column; a tool-head adjust-

ably mounted on the arm; a spindle rotatably journaled in said tool-head; a single speed prime mover located remote from said tool-head; a power transmission extending lengthwise of said arm; a single speed driving connection between said prime mover and said transmission; and change speed mechanism embodied in said tool-head and operatively connecting said power transmission with said spindle for giving to the latter rotation at 70 more than twelve different rates from a single rate in said prime mover and transmission.

In witness whereof, we have hereunto subscribed our names.

HENRY M. NORRIS.
